[57] CLAIM

The ornamental design for a medicament dispenser for children, as shown.

DESCRIPTION

FIG. 1 is a perspective view of a medicament dispenser for children, with the head or plunger portion extended, showing our new design;

FIG. 2 is a side elevational view thereof with the head or plunger portion contracted;

FIG. 3 is a rear view thereof;

FIG. 4 is a top plan view thereof; and

FIG. 5 is a bottom plan view thereof.
